US00D997247S

(12) **United States Design Patent** (10) **Patent No.:** **US D997,247 S**
(45) **Date of Patent:** **** Aug. 29, 2023**

(54) **GAMEPAD**

(71) Applicant: **Dongguan King Sheng Electronics Technology Co., Ltd.**, Guangdong (CN)

(72) Inventor: **JianWu Wang**, Guangdong (CN)

(73) Assignee: **Dongguan King Sheng Electronics Technology Co., Ltd.**

(**) Term: **15 Years**

(21) Appl. No.: **29/760,493**

(22) Filed: **Dec. 2, 2020**

(30) **Foreign Application Priority Data**

Jun. 5, 2020 (CN) 202030281151.5

(51) **LOC (14) Cl.** **21-01**

(52) **U.S. Cl.**

USPC **D21/333**

(58) **Field of Classification Search**
